UNITED STATES PATENT OFFICE.

VICTOR L. RONCI, OF BROOKLYN, NEW YORK, ASSIGNOR, BY MESNE ASSIGNMENTS,
TO WESTERN ELECTRIC COMPANY, INCORPORATED, A CORPORATION OF NEW
YORK.

ELECTRON-DISCHARGE DEVICE.

Application filed February 21, 1925. Serial No. 10,753.

This invention relates to electron discharge devices and has for an object an improved supporting structure for one of the electrodes, which is capable of withstanding 5 high voltages.

This object is attained in a device of this character, by providing a highly refractory wire nest comprising two parallel helices of large diameter with smaller diameter turns 10 at each end thereof. The smaller turns of each helix are interwoven to accommodate a supporting rod which is fused to one of the turns. A cylindrical insulating insert having an undercut portion is seated in each 15 large helix and carries a metallic hook for the suspension of the cathode. This arrangement provides an easily formed structure for the cathode support in which the curved surfaces of the nests prevent the high 20 voltages forming an arcing path from the anode.

Referring to the drawings:

Fig. 1 is an electron discharge device with a part broken away to illustrate the invention.

Fig. 2 is an enlarged perspective view of the electrode support made in accordance with this invention.

Fig. 3 is an end view of the support.

Fig. 4 shows the individual nests before assembly, and

Fig. 5 illustrates a winding tool for forming the wire nests.

The electron discharge device comprises 35 an enclosing vessel having a glass portion 10, and a cup-shaped metal anode portion 11. A helical wire grid 12 is coaxially supported within the vessel in a well-known manner. Centrally arranged within the 40 grid 12 and the anode 11 is the supporting rod 13, preferably of highly refractory material, such as molybdenum. The supporting rod 13 is provided with an undercut portion 14 at one end to receive the small turns 45 of the wire nests 15 and 16. A shoulder 17 on the rod acts as a positioning means for the nests.

The nests 15 and 16 are preferably formed 50 of highly refractory wire, such as molybdenum, and consist of closely wound helices of large diameter, each of the nests being wound in an opposite direction with respect to the other. One or more turns at the ends 55 of each helix may be provided with a flattened portion 18 to provide holding means

for the insulating inserts, to be hereinafter described. Flattened portions 18 are arranged on opposite surfaces of the helix to distribute the pressure on the insulating insert. Integral with each helix and at opposite ends thereof are one or more turns 19 and 20 of small diameter. These turns are arranged with their axes parallel with the axis of the large helix and are in alignment with each other.

The nests 15 and 16 are arranged in parallel relation with their smaller turns interwoven to provide a passage for the undercut portion 14 of the rod 13. The end 21 of the rod projecting above the small turns 20 70 is fused by drawing an arc over the tip thereof, thereby forming a button 22. The fusing operation melts the end of the rod and a rigid connection between the turns 20 and the rod is secured. A cylindrical insulating insert 23, composed of "lavite" or "alundum" is provided with an undercut portion 24 at each end and on opposite surfaces of the insert. In assembling the insert in the large helix, the turn having the 80 flattened portion 18 is sprung, to allow the passage of the insert through the helix. When the projection 25 reaches the other flattened portion 18, the insert is securely 85 clamped in the helix, since the first flattened portion 18 on the other end of the helix automatically falls into the undercut portion 24 at the other end of the insert.

This arrangement provides a rigid, highly insulated supporting structure for 90 the cathode 26, which is suspended from hooks 27 held in any desirable manner in the insulating inserts 23. Furthermore, the absence of sharp points in the metal portion of the insert of the support prevents the establishment of arcing paths from the anode which carries an extremely high potential.

The molybdenum wire nests of this invention may be formed by winding on a mandrel, such as is shown in Fig. 5. This tool 100 comprises a head 28, which may be inserted in the chuck of a lathe. One end of the head is provided with apertures 29 and 30, for the insertion of different size pins. A relatively short pin is inserted in the aperture 29 and a long pin of the desired diameter for the small turns of the helix, is inserted in the central aperture 30. The molybdenum wire is inserted in the space between the two pins and the head is rotated to make 110

a complete loop of the molybdenum wire. This operation provides the small diameter turn 19. The central pin is removed and replaces the short pin in aperture 29. A larger diameter pin 31 is inserted in the central aperture 30 and is provided with undercut portions 32 and 33 at opposite ends of the pin and on opposite surfaces thereof. The portion 32 is positioned adjacent the pin in aperture 29. The small diameter turn 19, of the molybdenum wire is placed on the pin in aperture 29. One or more turns are then wound on the undercut portion 32. These turns are wound in an opposite direction with respect to the small turn. A desired number of turns are then wound on the cylindrical portion of the pin 31, to provide the major portion 15 of the nest and a single turn is made over the undercut portion 33. The short pin in the aperture 29 is removed and a long pin 34 is inserted through the small turn 19 and into the aperture 29.

One or more turns 20 are then wound on the pin 34 in the same direction as the turn 19, and the completed nest is removed from the pins. The nest 16 is formed in like manner. This method provides an easily formed unit which may be interwoven to provide a complete metallic receptacle of highly refractory material for the support of the insulating inserts which carry the cathode.

Although the invention has been described with respect to a particular arrangement, it is understood that various modifications may be made in the construction, without departing from the scope of the invention. Furthermore, the invention is not limited to highly refractory wire, since the nests may be formed of any metal in wire form, and is only to be limited within the scope of the appended claims.

What is claimed is:

1. An electrode support comprising a wire helix of large diameter, a turn of small diameter at each end thereof and having its axis parallel to the axis of said large helix, an insulating member rigidly held on said helix, a supporting rod passing through said smaller turns, and an electrode supported from said member.

2. An electrode support comprising a wire helix of large diameter, a turn of smaller diameter at each end thereof and having its axis parallel to the axis of said large helix, a cylindrical insulating insert within said helix, means at either end of said helix to clamp said insert therein, a rod passing through said smaller turns and fastened thereto, a hook rigidly held in said insert and an electrode suspended from said hook.

3. An electrode support comprising a wire helix of large diameter, a turn of smaller

diameter at each end thereof and having its axis parallel to the axis of said large helix, an insulating member in said helix, retaining means on said helix to prevent movement of said member, a supporting rod passing through said turns and fused to one turn thereof, and a filament carried by said insulating member.

4. An electrode support comprising a wire helix of large diameter, a turn of smaller diameter at each end thereof and having its axis parallel to the axis of said large helix, an insulating member having an undercut portion, a flattened turn of said helix cooperating with said undercut portion to prevent movement of said member, a rod fastened to said helix, and a filament supported by said member.

5. An electrode support comprising a wire helix of large diameter, at least one of the turns of said helix having a flat portion, an insulating insert within said helix, said insert being retained therein by said flat portion, a plurality of turns of smaller diameter projecting from either end of said helix, a supporting rod, said turns being in alignment to receive said rod, a metallic hook in said insert, and a filament supported from said hook.

6. An electrode support comprising parallel wire helices of large diameter, each of said helices having a turn of small diameter at each end thereof, said turns being intermediate the large helices and having a common axis, a rod passing through said turns, an insulating member in each of said helices, and a filament supported by said members.

7. An electrode support comprising parallel wire helices of large diameter, each of said helices having a turn of small diameter at each end thereof, said turns being intermediate the large helices and interwoven to form sleeves, a rod passing through said sleeves, insulating members frictionally held in said helices, and an electrode supported from said members.

8. In an electron discharge device, an enclosing vessel comprising a glass portion and a metal portion, said metal portion constituting the anode of the device, a cathode within said anode, a support therefor, said support comprising a metallic rod, parallel cylindrical wire nests having integral turns of smaller diameter at each end thereof, said turns being interlocked to form receptacles for said rod, cylindrical insulating inserts in said nests, and means carried by said inserts for suspending said cathode therefrom.

In witness whereof, I hereunto subscribe my name this 16th day of February, A. D. 1925.

VICTOR L. RONCI.
